UNITED STATES PATENT OFFICE.

ALFRED PLANT, OF KEYPORT, NEW JERSEY.

DESIGN FOR TILING.

SPECIFICATION forming part of Design No. 34,742, dated July 2, 1901.

Application filed May 18, 1901. Serial No. 60,947. Term of patent 7 years.

To all whom it may concern:

Be it known that I, ALFRED PLANT, a citizen of the United States, residing at Keyport, in the county of Monmouth and State of New Jersey, have invented and produced a new and original Design for Tiling; and I do hereby declare the following to be a full, clear, and exact description of the invention, such as will enable others skilled in the art to which it appertains to make and use the same.

This invention relates to tiling, and in the accompanying drawings Figure 1 is a plan view showing my new design. Fig. 2 is an edge view of my tiling.

15 The design consists of the combination of two square blocks of the same size, but showing different figures, and placed so that similar blocks touch at the corners. The blocks are made up of a plurality of small square and oblong rectangular pieces laid closely together. The essential feature in the distinctive ornamentation of each block is herein after set forth.

25 One block A consists of two narrow parallel marginal bands *a b*, an intermediate wider

band *c*, two inner narrow parallel bands *e f*, having reentrant angles at the corners and square spots *g* in the square spaces *d*, into which the band *c* enlarges at the corners. The center *h* thus has a cruciform shape with very 30 short arms. The other block B has an outer margin of square blocks *i*, equaling in width the two bands *a b*, two narrow bands *k l*, similar to the bands *a b*, a wider band *m*, then two narrow bands *n o*, similar to *k l*, and a 35 square center *p*. These blocks A B are so grouped that they alternate with one another, the corners of similar blocks touching.

Having thus described my invention, what I claim, and desire to secure by Letters Patent, is—

The design for tiling, substantially as herein shown and described.

In testimony whereof I affix my signature in presence of two witnesses.

ALFRED PLANT.
